INVENTOR:
Charles H. Shamel

UNITED STATES PATENT OFFICE.

CHARLES H. SHAMEL, OF STONINGTON, ILLINOIS.

INTERNAL-COMBUSTION ENGINE.

Application filed November 30, 1921. Serial No. 519,032.

To all whom it may concern:

Be it known that I, CHARLES H. SHAMEL, a citizen of the United States, living at Stonington, Illinois, have invented a new 5 and useful Internal-Combustion Engine, of which the following is a specification.

My invention relates to improvements in internal combustion engines in which gaseous, vaporized or liquid fuel is burned by 10 injection into highly compressed air heated by such compression, or in which such fuel is mixed with air, compressed and ignited, such combustion occurring in a cylinder closed at one end and the resulting expansive 15 energy of the hot gases produced used to actuate the reciprocating piston which closes the other end of the cylinder and thus by ordinary intermediate apparatus of connecting rod, crank shaft, etc., made 20 to perform work.

As is well known, the four cycle type, is the most used form of internal combustion engines. Although two cycle engines are simpler in construction and furnish approximately 25 twice as much power as a four cycle engine of the same size and number of cylinders, they are, nevertheless, owing to a number of causes, not nearly so frequently used at the present time as four cycle engines, particularly in the various kinds of 30 motor vehicles.

The purpose of my invention is to furnish a two cycle internal combustion engine which will eliminate the objectionable features and supply a two cycle engine which will be as reliable and economical in operation, simpler and cheaper in construction and approximately twice as powerful for the same size and number of cylinders as a 35 four cycle engine. I accomplish this purpose by mechanism, one form of which is illustrated in the accompanying drawings, in which—

Figure 1 is a perspective external view of 40 the cylinders and cylinder head extensions of a two cylinder unit.

Figure 2 is a perspective view of the piston for the left hand cylinder of Figure 1.

Figure 3 is a cut-away view showing the 45 relative interior arrangement of the various cylinders and pistons.

Figure 4 is a horizontal section on the line 4—4 of Figure 1.

Figure 5 is a top profile view of Fig. 1. 50 Figure 6 is a horizontal section showing a modified form of admission valves, here-

after described, on a horizontal section corresponding to 4—4 of Figure 1.

Similar numerals refer to similar parts throughout the several views. 60

This engine must be constructed in units, each containing two combustion cylinders and accessory mechanism. Referring to Figures 1 to 4, 1 and 2 are the left and right cylinders respectively of a two-cylinder unit the diameter of the lower third of which is from one third to three fourths greater than the diameter of the upper two thirds, the left wall of the left cylinder being straight with all of excess diameter of 65 the lower third on the right side. Likewise the right side of the right cylinder is straight, with all of the excess diameter of the lower third on the right side. 70

3 and 4 are small cylinders rising 75 from the excess diameter of the lower third of 1 and 2. 5 and 6 are cylinder head extensions having a capacity equal to the desired clearance, each of which connects the middle part of small cylinders 4 and 3 respectively with the top of large cylinders 1 and 2 respectively, that is, 6 connects 2 with 3 and 5 connects 1 with 4. 7, 7, are spark plugs; 8 and 9 are pistons. There are two of these, one for the right, the other 80 for the left cylinder but otherwise identical. These are each made of three parts, 20, 21 and 22, rigidly fastened together, each of said parts fitting the corresponding part of the cylinders 1 and 3; each of these 85 parts of the pistons 8 and 9 have piston rings, 12, 13, 14, 15, 16, 17, 18 and 19 for making (with proper lubrication) gas tight joints with the corresponding parts of the cylinder. More piston rings may be 90 used wherever needed to make gas-tight joints. 24 is a slot in the small piston 21, corresponding to the end of the head extension 6 into the small cylinder 3; 42 is a 95 corresponding slot in the small valve piston 100 member of the piston group 9. 33 and 34 are open chambers in communication with the interior of piston 21 and the corresponding part of the right piston by the openings 23, formed by the upward extension of the 105 walls of the wide lower third of 1 and 2. A part of these spaces are cut off by proper walls to form the spaces 35, 36, 37, 38, which are filled with cooling water, being in communication with the ordinary water jacket 110 of an internal combustion engine (water jacket not shown in drawings); 23 are

openings in the lower portion of the part 21 of the piston 8 and the corresponding part of piston 9 so that there is communication at all positions of its stroke between the space 33 and the interior of said part 5 21, the upper end of which is open and the same for the corresponding part of piston 9 and space 34. 25 and 27 are connecting rods between the pistons 8 and 9 and the 10 crankshaft 26 which revolves in the bearings 30; 31 and 32 are inwardly opening valves for the admission of pure air or fuel and air mixed (from pipes not shown) into the partial vacuum created in spaces 33 and 15 34 when the piston 8 moves downward. 3' and 4' of Figure 6 show a modified form of admission valves each of which is of sufficient diameter to occupy nearly all of the 20 space between the upper parts of the main cylinders in which parts combustion occurs. In this form approximately the upper two thirds only of the piston admission valves 3 and 4 are cylindrical being mounted on and actuated by stems 44 and 45 extending 25 upward from the outer edge of larger lower third of the pistons 8 and 9.

In this type of internal combustion engines of such size that the pressure during the working stroke on the admission valve 30 pistons 21 and 22 is objectionable such pressure can be entirely neutralized by a slight enlargement of the whole diameter of the cylinders 3 and 4 at the places, 46 and 47, where the extension of the head of the 35 opposite cylinder joins on, so that the pressure in the combustion cylinder during the working stroke will be transmitted to all sides of the said valve pistons thus be entirely balanced or neutralized.

40 The operation of the engine, when using as combustible either a mixture of natural or illuminating gas and air or of gasoline vapor and air (which are the combustibles for which the form shown in the figures are adapted) is as follows: Assume that piston 8 is in the position shown in Figure 3 and that the compressed mixture of gas and air has been ignited by the properly timed spark from the spark plug 7; this will force the entire piston 8 downward and the part 22 thereof will create a partial vacuum in the space 33, which will open the valve 31 and thus admit (through a connecting pipe not shown) the combustible mixture so that when the piston 8 is at the bottom of its downward stroke all of the excess lower third of the cylinder 1, the space 33 and the interior of 45 the small cylinder 3 will be filled with such combustible mixture, it being assumed that the space 33 and interior of 21 were already filled with said mixture, then when the piston 8 moves upward by the action of the crank 26, the part 22 thereof will compress 50 this combustible mixture and force it into

33 and the interior of 3 until the opening 24 in 21 comes opposite the corresponding opening in the wall of 3 into the head 6; at this moment the piston 9 will be at the bottom of its stroke and will have uncovered the exhaust port 11 through which the products of the previous combustion will rush out; this releases the pressure in the cylinder 2 just before the connection is made, as above described, with the compressed combustible mixture in 33 and 3, consequently said mixture will rush through 24 and 6 into the top of 2 and expel the products of the previous combustion through the port 11 and likewise at 75 the same time fill 2 with a fresh charge of combustible mixture; by the time this is accomplished the piston 9 will have started on its upward move which will close the exhaust port 11 at the same instant that the part 21 of piston 8 has moved down the same amount, thus moving the opening 24 therein below the opening through 3 into the end of the head 6, so that the charge of combustible mixture 80 will be entirely confined and consequently compressed by the upward movement of the head 40 of the piston 9 until it is ignited by the properly timed spark from the spark plug 7 when piston 9 is at or near the top of its movement according to desired timing of the ignition; the ensuing combustion then forces the piston 9 downward whereupon the same process of suction of combustible mixture and subsequent compression and combustion thereof takes place in the various parts of cylinder 1 as just described for cylinder 2, and this action 85 continues alternately so long as the engine 90 operates.

95 This engine can also be very advantageously used with liquid fuel such as kerosene, crude oil, alcohol, etc., by replacing the spark plug 7 with the oil injecting apparatus shown in detail in Figure 2 of my application No. 459,374, series 1915, for a patent for an improvement in internal combustion engine, in which case it would also be necessary in order to actuate such injecting apparatus, to have a projection in the center of the parts 20 and 36 of cylinders 8 and 9 respectively similar to that shown at 34, Figure 1 in my said previous application No. 459,374. If operated with said injecting apparatus only pure air would be drawn in through the valves 31 and 32.

100 It will be at once perceived by those familiar with the operation of the various types of internal combustion engines that my invention will have important advantages over existing types of two cycle engines particularly in the following respects, among others:

105 1. It will eliminate the serious troubles

arising from compressing the combustible mixture in the crank case such as leakage of combustible mixture, dilution of lubricating oil by gasoline, difficulty of access to bearings, etc., and will also enable the compression of the mixture to be adjusted as desired by varying the relative size of the mixture compressing parts of the pistons and cylinders. Scavenging can be made especially effective where liquid fuel is being used, and pure air compressed as when using the injection apparatus shown in my said application No. 459,374, because the compression of the air to be introduced can be so adjusted that nearly all of the products of combustion will be driven out or "scavenged."

2. The injection of the fuel at the top of the power cylinder instead of at the side as in ordinary two cycle internal combustion engines will permit much better scavenging with no loss of combustible such as occurs in the ordinary two cycle form in which in spite of the deflecting rib on the top of the piston, some of the combustible mixture rushes directly across to the exhaust port and passes out with the spent gases before that port is closed. If the combustible mixture is admitted at the top this will not occur and by proper adjustment and particularly the use of exhaust ports on two or more sides of the cylinder with a slightly elevated center of the piston the scavenging can without loss of combustible mixture be made superior to that of the best four cycle type so that instead of this form of two cycle engine being inferior like ordinary two cycle engine to the four cycle type, in the amount of brake horse power secured from a given amount of fuel it will be superior and furnish more power from the same amount of fuel.

I expressly disclaim limiting myself to the particular construction shown in the accompanying drawings and description for the principles therein embodied can also be used in other forms and constructions of internal combustion engines such as horizontal, inclined, opposed, etc., and with other methods of power transmission than connecting rod and crank.

I claim—

1. In a two cycle internal combustion engine, in combination, two main cylinders,

each with a curved top extended in diminishing size to form a duct which meets a small cylinder rising from the top of the other main cylinders, thereby furnishing means for introducing into the combustion chamber of such other cylinder combustible mixture previously lightly compressed. 55

2. In a two cylinder internal combustion engine, each cylinder comprising a combustion chamber and a separate compression chamber, pistons for each cylinder, separate means positively actuated by each piston to connect its separate compression chamber with the combustion chamber of the other cylinder. 60

3. In a two-cylinder, two cycle, internal combustion engine, each cylinder comprising a combustion chamber and a separate compression chamber, pistons for each cylinder, and separate means positively actuated by each piston to connect its separate compression chamber with the combustion chamber of the other cylinder. 70

4. In a two-cylinder internal combustion engine, each cylinder comprising a combustion chamber, and a separate compression chamber, pistons for each cylinder and separate means, positively actuated by each piston, to connect its separate compression chamber with the top of the combustion chamber of the other cylinder. 80

5. In a two-cylinder internal combustion engine, each cylinder comprising a combustion chamber and a separate compression chamber, pistons for each cylinder and separate means consisting of a piston valve attached to each piston and positively actuated thereby, to connect its separate compression chamber with the combustion chamber of the other cylinder. 90

6. In a two-cylinder internal combustion engine, each cylinder comprising a combustion chamber and a separate compression chamber, pistons for each cylinder, separate means consisting of a piston valve attached to each piston and positively actuated thereby to connect its separate compression chamber with the top of the combustion chamber of the other cylinder. 95
